TOOL HANDLE CONNECTION

Michael Z. Andrews, Chula Vista, Calif.

Application March 20, 1950, Serial No. 150,764

3 Claims. (Cl. 306—40)

1

My invention relates to a combination tool, more particularly to a tool which is adapted for use in gardening or the like, and the objects of my invention are:

First, to provide a combination tool of this class which may be readily and easily employed alternately as a hoe or a spade;

Second, to provide a combination tool of this class which is very simple and easy to adjust and convert from one tool to another;

Third, to provide a combination tool of this class which incorporates novel construction of the metal parts, all of which may be made of sheet metal, and tubular stock, with the exception of one bolt, whereby an economical mass production article may be made available to the public;

Fourth, to provide a combination tool of this class having a novel blade structure, wherein a loop neck portion thereof is formed integral therewith, and is provided with corrugated notch portions providing adjustment about the axis of the loop portion for converting the tool from one type of tool to another, providing a tool having combined rigidity, strength and simplicity;

Fifth, to provide a tool of this class which is very simple to fabricate and assemble;

Sixth, to provide a tool of this class which is very strong and rigid in proportion to the amount of metal used therein; and

Seventh, to provide a combination tool of this class which is very simple and economical of construction, efficient in operation, and which will not readily deteriorate or get out of order.

With these and other objects in view, as will appear hereinafter, my invention consists of certain novel features of construction, combination and arrangement, of parts and portions, as will be hereinafter described in detail and particularly set forth in the appended claims, reference being had to the accompanying drawings and to the characters of reference thereon, forming a part of this application, in which:

Fig. 1 is a top or plan view of the tool, showing the handle fragmentarily, and illustrating by dash lines a varying position of the blade for use as a shovel or the like; Fig. 2 is an enlarged fragmentary sectional view, taken from the line 2—2 of Fig. 1; Fig. 3 is a sectional view, taken from the line 3—3 of Fig. 2; and Fig. 4 is a fragmentary sectional view, taken from the line 4—4 of Fig. 2.

Similar characters of reference refer to similar parts and portions throughout the several views of the drawings.

The blade 1, yoke 2, bolts 3, blade locking bear-

2

ing 4, ferrule 5, nut 6, pin 7, and the handle 8, constitute the principal parts and portions of my combination tool.

The blade 1 is made of sheet metal, and is provided with a flat portion 1a, having a soil working edge 1b and opposed to the soil working edge 1b the blade 1 is provided with a neck portion 1c, which is formed into a loop shape, which is channel-shaped in cross-section, as shown best in Figs. 3 and 4 of the drawings. This loop shaped neck 1c is substantially arcuate, and the extended end portion 1d thereof is preferably welded or otherwise rigidly fixed to the blade 1, all as shown best in Fig. 2 of the drawings. It will be noted that the neck portion 1c is integral with the blade 1, and the channel-shaped in cross-section neck portion 1c is provided with a plurality of laterally disposed indented portions 1e, which are engageable with the edge portions 4a of the blade locking bearing 4 at the opening therein.

These edges 4a define the edges of the opening in the blade-locking bearing 4, and are preferably case-hardened, so that they are durable, and the notch portions 1e of the neck 1c are preferably case-hardened, providing very strong, durable structure for locking the blade 1 in certain angular position relative to the handle 8; so that it will withstand considerable hard usage. It will be noted that the blade locking bearing 4 is substantially circular, as shown in Fig. 3, and provided with a surrounding flange portion 4b, which surrounds the end of the ferrule 5 and extends axially thereof.

The ferrule 5 is provided with a tapered portion 5a, fitted over the handle 8, and this tapered portion 5a surrounds the opposite ends of the pin 7, which extend through the tubular nut 6 into which the bolt 3 is screw-threaded, as shown in Fig. 2 of the drawings. The head of the bolt 3 is retained by the yoke 2, which extends into and engages the channel-shaped portion of the neck 1c of the blade 1. This yoke 2 is preferably made of a single piece of sheet metal, and at its middle portion is provided with an opening 2a, through which the bolt 3 extends. Opposite ends 2b and 2c are spot-welded together internally of the neck loop portion 1c, all as shown best in Figs. 2 and 4 of the drawings.

As shown in Fig. 4 of the drawings, the end portions 2b and 2c are provided with offset portions 2d and 2e, which engage the edges of the channel-shaped in cross-section loop neck 1c, providing firm engagement of the yoke 2 with the loop neck 1c for holding the same in positive engaged relation with the blade locking bear-

ing 4, which abuts the end of the ferrule 5, all as shown best in Figs. 2 and 4 of the drawings.

It will be here noted that the blade 1 is provided with a formed rib portion 1f, substantially at the middle thereof, aligning with the portion 1d, which straddles the same, for reinforcing the juncture of the channel-shaped in cross-section loop neck 1c with the blade 1.

The operation of my combination tool is substantially as follows:

When the tool is being used in the form of a hoe, as shown in Fig. 2 of the drawings, it may be readily converted to a shovel, as indicated by dash lines A in Fig. 1 of the drawings, by rotating the handle 8 in a counter-clockwise direction relative to the blade 1, which loosens the nut 6 on the bolt 3 and provides clearance of the edge portion 4a of the blade locking bearing 4 relative to the lateral serrations 1e in the channel-shaped in cross-section loop neck 1c of the blade 1.

Thus, the blade 1 is permitted to rotate into the dash line position A about the axis of the loop neck portion 1c, as shown in Fig. 2 of the drawings, until the blade 1 is substantially parallel to the axis of the handle 8. The handle 8 may then be rotated in a clockwise direction relative to the blade 1, causing screw-threaded tightening of the bolt 3 in the nut 6, which is retained by means of the pin 7 in the handle 8. It will be noted that as the nut 6 is tightened relative to the bolt 3, the blade locking bearing 4, at its edge portions 4a surrounding the central opening therein, engages the serrations 1e of the channel-shaped in cross-section loop neck 1c, due to the tension created in the yoke 2 by the bolt 3. Axial bearing of the blade locking bearing 4 on the end of the ferrule 5 causes the tapered portion 5a thereof to be more tightly forced upon the end of the handle 8 in surrounding relation with opposite ends of the pin 7, which concurrently retains the nut 6 and the handle 8 in fixed relationship to each other.

It will be noted that the offset portions 2d and 2e, shown in Fig. 4 of the drawings, are arcuate, as illustrated in Fig. 2 of the drawings provide a conforming bearing relationship with the edges of the channel-shaped in cross-section loop neck 1c for efficiently holding the serrations 1e in secure engaged relationship with the edge portion 4a of the central opening in the blade locking bearing 4.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. A blade and handle connecting means com-

prising a ferrule surrounding a portion of a handle and having a nut mounted internally of said ferrule, a cylinder having one exterior side thereof integral with a blade, said cylinder having serrations on a part of the circumference remote from the blade, a yoke member within said cylinder having arms extending radially outwardly therefrom and straddling said cylinder adjacent said serrations, a bolt having a head engaging the yoke and a shank threaded into said nut, a blade locking member secured to the ferrule adjacent the cylinder and engaging said serrations when said nut and bolt are tightened relative to each other to hold the blade in fixed relationship.

2. A mounting means for a tool blade comprising a ferrule, a threaded nut recessed within said ferrule, a cylinder having one exterior side thereof integral with a blade, said cylinder having serrations on a part of the circumference remote from the blade, a yoke member within said cylinder having arms extending radially outwardly therefrom and straddling said cylinder adjacent said serrations and extending into said ferrule, a bolt having a head held by said yoke and a shank threaded into said nut, a cup shaped blade locking member frictionally secured to the end of said ferrule adjacent said cylinder and having a rectangular aperture therein engaging said serrations on said cylinder when said nut and bolt are tightened relative to each other to hold the blade in fixed relationship whereby said blade may be adjusted to a position parallel to said handle or at a right angle thereto.

3. A blade-handle mounting means comprising a handle-receiving ferrule, a nut mounted internally of said ferrule, a yoke member having an aperture therein and tabs adjacent thereto, a bolt having a shank extending through said aperture and held by said tabs, said shank being screw-threaded and received by said nut, a hollow cylinder integral with a blade and having external serrations thereon remote from the blade, said yoke having bifurcated ends straddling said cylinder walls and said ends being secured together internally of said cylinder and intermediate the ends thereof, a blade locking member having a substantially rectangular opening being parallel to and engaging said serrations when said bolt shank and said nut are threadably engaged, and said blade locking member having a downturned flange slidable over the end of said ferrule.
